UNITED STATES PATENT OFFICE.

ROBERT T. POLLOCK, OF BOSTON, MASSACHUSETTS, ASSIGNOR TO UNIVERSAL OIL PRODUCTS COMPANY, OF CHICAGO, ILLINOIS, A CORPORATION OF SOUTH DAKOTA.

PROCESS AND APPARATUS FOR CRACKING PETROLEUM OIL.

Application filed December 6, 1920, Serial No. 428,790. Renewed October 6, 1926.

This invention relates to improvements in process and apparatus for cracking petroleum oil and has as its salient feature subjecting the reflux condensate and raw oil or 5 reflux condensate alone to distillation at atmospheric pressure or under a lower pressure than that at which the main apparatus is operated. The object of this is to prevent oil already sufficiently light from being 10 returned to the system for cracking.

In the drawing, the single figure is a view partly in section and partly in side elevation, of my improved apparatus for carrying out the process.

15 Referring in detail to the drawing, 1 designates the furnace in which is mounted the heating coil 2. This heating coil 2 which may be of 2" to 6" pipe has its upper or discharge end connected by transfer line 20 3 provided with a suitable throttle valve 4 to vapor chamber 5. This vapor chamber 5 has liquid drawoff 6 provided with throttle valve 7, vapor outlet pipe 8 having throttle valve 9' and a downwardly inclined extension 9 leading to the lower side of dephlegmator 10. This dephlegmator 10 is provided with suitable baffles 12 and at its upper end has a nipple 13 connected to vapor outlet pipe 14, the latter having throttle valve 15. 25 The pipe 14 in turn is connected to condenser coil 16 seated in condenser box 17. The condenser coil 16 is connected at its lower end by pipe 18 having throttle valve 19 to the upper part of receiver 20. This receiver 30 35 20 is provided with pressure gauge 21, liquid level gauge 22, gas outlet pipe 23, having throttle valve 24, liquid drawoff pipe 25 having throttle valve 26. Raw oil is supplied by pump 27 and feed line 28 provided with 40 45 50 throttle valve 29, the pipe 28 being connected to nipple 30 at the upper end of the dephlegmator. The lower end of the dephlegmator is connected by line 31 to the still 32. This still 32 is mounted in suitable setting 33 and 55 60 65 70 75 80 85 90 95 100 105 110 is adapted to be heated by the flue gases from the flue 34 leading from the furnace. In other words, the flue gases are utilized for heating the still 32. The unvaporized portion of the oil in the still 32 including both raw oil and reflux condensate is delivered by feed line 36 and pump 36' to the heating tubes 2. The still 32 is provided with the vapor outlet 38 having throttle valve 39 leading to condenser coil 40 seated in condenser box 41. The lower end of the coil is con-

nected to the upper part of receiver 42, which receiver is equipped with an outlet pipe 43 having throttle valve 44. The arrangement is such that the reflux condensate and preheated fresh oil are delivered to the still 32 where they may be heated to a temperature of say, 450 degrees F., if that is the end point of gasoline desired, so as to drive off those oil constituents which are already sufficiently light. The unvaporized portion is delivered to the feed line 36 and pump 36' to the heating coil 2. If desired, instead of feeding the raw oil into the dephlegmator, the valve 29 may be closed and raw oil drawn in by the pump 36' through line 45 having valve 46 and connected to the feed supply. In this case only the reflux condensate will be subjected to distillation in the still 32.

In carrying out the process, the coil 2 and the vapor chamber, the dephlegmator as well as the associated water condenser and receiver may be maintained under a pressure of say, 151 pounds to the square inch, and the oil while in liquid phase at a temperature of say, 700 degrees F., assuming petroleum gas oil is used. The reflux condensate either mixed with the preheated raw oil from the dephlegmator or alone may be distilled at atmospheric pressure and heated to say, 450 degrees F., or it may be distilled under a pressure of say, 50 pounds and a temperature of 500 degrees F., so as to produce a slight cracking. However, normally I believe it would be better to distill this reflux condensate at atmospheric pressure. The process may be further modified by distilling the reflux condensate either mixed with the preheated raw oil or of itself under a vacuum, which can be accomplished by putting a vacuum pump (not shown) on the outlet line 43.

I claim as my invention:

1. A process of cracking petroleum oil, consisting in subjecting the oil to a cracking temperature under a superatmospheric pressure to cause substantial vaporization, subjecting the generated vapors to a reflux condensing action by passing them, prior to any substantial cooling action, to a reflux condenser, delivering the reflux condensate to a still where it is subjected to distillation at atmospheric pressure to vaporize those constituents that are of the desired predetermined end point, then returning the un-

vaporized liquid from the atmospheric still to the cracking zone, and in heating said atmospheric still.

2. A process of cracking petroleum oil, 5 consisting in subjecting the oil to a cracking temperature under a superatmospheric pressure to cause substantial vaporization, subjecting the generated vapors to reflux condensing action by passing them directly to 10 a reflux condenser also maintained under a superatmospheric pressure, delivering reflux condensate to a still where it is subjected to distillation at substantially atmospheric pressure to release those constituents that 15 are of the desired predetermined end point, then returning the liquid portions of said reflux condensate to the cracking zone, and heating said atmospheric still by the flue gases from the furnace of the cracking zone. 20 3. A process of cracking petroleum oil consisting in heating the oil to a cracking temperature to cause substantial vaporization, subjecting the generated vapors to reflux condensing action by passing them, 25 prior to being subjected to any substantial cooling action, to a reflux condenser, delivering the reflux condensate separated from the vapors undergoing reflux condensation to a still where it is subjected 30 to substantially atmospheric distillation to release those constituents that are of the desired predetermined end point, then returning the liquid portions of said reflux condensate to the cracking zone, maintaining a 35 pressure on said cracking zone and reflux condenser in excess of 50 pounds to the square inch, and in heating said atmospheric still.
4. A process of cracking petroleum oil 40 consisting in heating the oil to a cracking temperature in a main cracking zone to cause substantial vaporization, subjecting the generated vapors to reflux condensing action by passing them directly to a reflux condenser, 45 delivering the reflux condensate to a still where it is subjected to atmospheric distillation to drive off those constituents that are of the desired predetermined end point, then returning the liquid portions of said reflux 50 condensate to the main cracking zone, maintaining a pressure on said cracking zone and reflux condenser in excess of 50 pounds to the square inch, and in heating said atmospheric still.
5. A process for converting high into low 55 boiling point hydrocarbons, consisting in cracking the oil in a heating zone under pressure, subjecting the oil vapors to a dephlegmating action in a reflux condenser, 60 condensing the low boiling point oil vapors subsequent to dephlegmation, recovering the low boiling point cuts from the reflux condensate by retreatment thereof in a zone of lower pressure than that maintained in the 65 reflux condenser and combining the unva-

porized reflux condensate from the zone of retreatment with raw oil prior to cracking.

6. A continuous process for converting high into low boiling point hydrocarbons, 70 consisting in cracking the oil in a heating zone under pressure of the generated vapors, subjecting the oil vapors to a dephlegmating action in a reflux condenser, condensing the low boiling point oil vapors subsequent to dephlegmation, recovering the low boiling point oil fractions from the reflux condensate in a zone of lower pressure than the reflux condenser, combining the unvaporized reflux condensate and raw oil in regulated proportions prior to cracking. 75

7. A continuous process for converting high into low boiling point hydrocarbons, 80 consisting in cracking the oil in a heating zone under pressure of the generated vapors, subjecting the oil vapors to a dephlegmating action in a reflux condenser, condensing the low boiling point oils subsequent to dephlegmation, recovering the low boiling point oil fractions from the reflux condensate in a heated zone of lower pressure than that maintained in the reflux condenser, combining the unvaporized reflux condensate and preheated raw oil in regulated proportions prior to cracking. 85

8. In an apparatus for converting high 90 into low boiling point hydrocarbons, the combination with a means for cracking the oil, of a reflux condenser for dephlegmating the generated oil vapors, means for delivering the generated oil vapors to said reflux condenser, condensing means for recovering the low boiling point vapors, a still connected to the reflux condenser adapted to extract the low boiling point oils from the reflux condensate, means for combining the reflux condensate with the raw oil prior to cracking, and means for maintaining a pressure upon the apparatus during operation. 95

9. A continuous process for converting high into low boiling point hydrocarbons, 100 consisting in cracking the oil in a heating zone under pressure of the generated vapors, subjecting the vapors to a dephlegmating action in a reflux condenser and passing the reflux condensate to a separate zone of treatment and there retreating it under a lower pressure than that maintained in the reflux condenser, separately condensing the distilled oil constituents from the separate 105 zones of treatment and returning the unvaporized reflux condensate and mixing it in controlled quantities with the oil charged to the initial heating zone. 110

10. A continuous process for converting high into low boiling point hydrocarbons, 115 consisting in cracking the oil in a heating zone under a pressure of the generated vapors, subjecting the evolved vapors to a dephlegmating action in a reflux condenser, retreating the reflux condensate under a 120

lower pressure than that maintained in the reflux condenser in a separate zone to recover additional low boiling point fractions, separately condensing the vapors

5 from the separate zones and returning the unvaporized reflux condensate and mixing it in regulated quantities with the charging oil supplied to the process.

11. A process for converting high boiling point hydrocarbons into low boiling point hydrocarbons, consisting in subjecting the oil to a cracking temperature in a heating zone, while under pressure of the generated vapors, in subjecting the vapors evolved 10 from the oil to dephlegmation, in retreating the reflux condensate resulting from such dephlegmation under a lower pressure, to separate substantial quantities of the lighter oil constituents therefrom, in uniting the 15 heavier constituents of the reflux condensate with the charging oil for the process in predetermined proportions, and in supplying the resulting mixture to the heating zone.

12. A process for converting high boiling point hydrocarbons into low boiling point hydrocarbons, consisting in subjecting the oil to be converted to cracking conditions in a heating zone, in dephlegmating vapors released from the oil in a dephlegmating zone, 20 in effecting a removal of the lighter from the heavier constituents of the heated reflux condensate without again subjecting said constituents to further treatment in the heating zone separated from the vapors undergoing dephlegmation, in a zone apart from the dephlegmating zone and in which no dephlegmating action of the vapors or substantial cracking of the oil is occurring, in recovering the lighter constituents removed 25 from the heavier constituents of the reflux condensate, and in continuously returning the heavier constituents of the reflux condensate to said heating zone for further treatment in the process.

13. A process for converting high boiling point hydrocarbons into lower boiling point hydrocarbons, consisting in subjecting the oil to a cracking treatment in a heating zone, in permitting vaporization of the oil in a suitable vapor space, in subjecting the vapors evolved from the oil to reflux condensation in a reflux condensing zone, in passing the heated reflux condensate separated from the vapors undergoing reflux condensation 50 to a separate zone, in which no substantial cracking takes place or dephlegmation of vapors occurs, wherein the reflux condensate is subjected to further treatment, to remove therefrom substantial quantities of the low boiling point fractions which have combined with the reflux condensate during the reflux condensing action, in recovering such low boiling point fractions and in continuously returning the heavier constituents of the reflux condensate, from which such lower boil-

ing point fractions were separated, to said heating zone, to be subjected to further treatment in the process.

14. A process for converting high boiling point hydrocarbons into low boiling point hydrocarbons, consisting in subjecting the oil to a cracking treatment in a heating zone, in transferring the heated oil from said heating zone to a second zone, where substantial vaporization occurs, in subjecting the 70 vapors generated from the oil to dephlegmation in a dephlegmating zone, in removing the reflux condensate separated from the vapors undergoing dephlegmation from the dephlegmating zone to an evaporating zone 75 wherein no substantial cracking or dephlegmating action occurs and wherein the lighter gasoline-like constituents are evaporated from the heated reflux condensate, in recovering the lighter constituents evaporated 80 from the heated reflux condensate, and in continuously returning the heavier constituents of the reflux condensate, subsequent to the removal of such lighter constituents, to the heating zone, to be again subjected to a 85 cracking treatment.

15. In an apparatus for cracking oil, the combination with a still, of a reflux condenser for receiving the vapors therefrom, means for conveying reflux condensate from 95 said reflux condenser to a separate zone, means for taking off light oil constituents in vaporous form from said second zone, means for maintaining a lower pressure in said separate zone than is maintained in said 100 reflux condenser, and means for returning heavier constituents of the reflux condensate from such separate zone to said still for further treatment.

16. A process for converting high boiling point hydrocarbons into relatively lower boiling point hydrocarbons, consisting in subjecting the hydrocarbon oil to cracking conditions of temperature and pressure in a still, in subjecting the vapors evolved from the oil to dephlegmation, in collecting the reflux condensate separated from the vapors, as a result of such dephlegmation, in a zone 105 wherein such reflux condensate is maintained out of contact with the undephlegmated vapors evolved from the oil undergoing conversion in the process, in effecting an evaporation of the light gasoline-like constituents from the heavier constituents of the heated 110 reflux condensate in such zone, in recovering 115 the evaporated light gasoline-like constituents, and in continuously returning the heavier unvaporized constituents of the reflux condensate, subsequent to the removal 120 of such light gasoline-like constituents therefrom, to the cracking still; to be again subjected to cracking conditions of temperature and pressure.

17. A process for converting high boiling point hydrocarbons into relatively lower 125

boiling point hydrocarbons, consisting in subjecting the hydrocarbon oil to be treated to cracking conditions of temperature and pressure in a still, in subjecting the vapors evolved from the oil to dephlegmation in a reflux condensing zone, in admitting the reflux condensate separated from such vapors to an evaporating zone in which the reflux condensate is maintained out of contact with the undephlegmated vapors passing from the still to the reflux condensing zone, where-
in the light gasoline-like constituents are evaporated from the heavier constituents of

the reflux condensate, and in assisting in the evaporation of such light gasoline-like constituents by the application of additional heat to the reflux condensate in said evaporating zone, in recovering the evaporated gasoline-like constituents, and in continuously returning the heavier unvaporized constituents of the reflux condensate, subsequent to the removal of the light gasoline-like constituents therefrom, to the cracking still to be again subjected to cracking conditions of temperature and pressure.
